His Attorney

UNITED STATES PATENT OFFICE.

LOUIS W. THOMPSON, OF SCHENECTADY, NEW YORK, ASSIGNOR TO GENERAL ELECTRIC COMPANY, A CORPORATION OF NEW YORK.

MAGNETIC TIME ELEMENT.

1,316,984.

Specification of Letters Patent. Patented Sept. 23, 1919.

Application filed February 16, 1918. Serial No. 217,849.

To all whom it may concern:

Be it known that I, LOUIS W. THOMPSON, a citizen of the United States, residing at Schenectady, in the county of Schenectady, 5 State of New York, have invented certain new and useful Improvements in Magnetic Time Elements, of which the following is a specification.

My invention relates to devices of the 10 character in which a time element is interposed between the initiation of an action and its completion and more specifically it relates to electro-magnetic switches in which an interval of time elapses between the act 15 which initials and the final act which completes. Various means have been devised for effecting such a time element, one of the commonest being the dash-pot. Electro-magnetic switches provided with a dash-pot 20 for delaying the action of a switch member are very commonly employed but because of inherent defects in the dash-pot they have not uniformly been regarded with favor. One of the objects of my invention is to provide 25 a time element device which is free from the difficulties experienced in the use of dash-pots and similar devices, and which is mechanically simple and uniformly effective.

30 In carrying out my invention I employ, as controlling elements, a magnet which is preferably a permanent magnet and an armature arranged so that it will normally be in contact with the magnet. One of these 35 members (in the form which I have shown as the magnet) is arranged to vibrate through its normal position and as it vibrates freely the amplitude will gradually decrease. During the vibration attractive 40 forces will not be sufficiently great to cause the movement into contact but as the amplitude decreases the attractive force increases as it approaches the normal position until finally the movement takes place. I have 45 found that if the vibratory member is mounted to move freely and it is always given the same initial deflection that the time limit will always be a perfectly definite one.

50 The device which I have shown is an electromagnetic switch in which the deflection of the pivoted magnet is controlled by an electromagnet, the deflection being maintained until the condition of the electro-magnet is reversed. The armature, which is

attracted by the permanent magnet, is arranged to operate a switch so that there will be a definite time interval between the reversal of the condition of the electromagnet and the operation of the switch. 60

In the accompanying drawing illustrating one form of my invention, Figure 1 is an elevation of a complete device; Fig. 2 is an end view of the same, and Fig. 3 shows one system of electrically connecting my improved switch.

Referring to Figs. 1 and 2, 10 represents a permanent magnet which I have shown as of the horseshoe type mounted in a bracket 11. This bracket 11 is secured to shaft 12 which is mounted in bearings 13. These bearings are preferably of the antifriction type, as, for instance, ball bearings, so as to permit the magnet to vibrate with a minimum amount of friction. Coöperating with 75 the permanent magnet is an armature arm 14 which is pivoted at 15 in a bracket 15' so as to rest against a stop screw 16 when it is not attracted by the magnet. As shown, the armature comprises an arm which may 80 be of non-magnetic material and a magnetic portion 17 of magnetic material which is attracted by the magnet. As shown, this magnetic portion is cylindrical in form and secured to the arm by a clamp 17' so as 85 to project on both sides of the arm opposite the pole pieces of the magnet. Thin non-magnetic sleeves 16' around the magnetic portion 17 prevent the latter from "freezing" to the magnet. The switch, 90 which is operated by the armature, comprises a bell crank member 18 pivoted at 19, provided with a contact member 20 co-operating with a stationary contact 21. The contacts 20 and 21 are held in engagement 95 by a spring arm 22 which engages the end of the bell crank lever. An electromagnet 23 acts on the spring arm and by pulling it downward forces the arm 14 downward slightly so as to assist in releasing the arm 14 from the magnet 10.

The vibratory or reciprocatory movement of the magnet 10 is initiated by electromagnet 24 having an armature 25 pivoted at 26. Attached to the armature 25 is a finger 27 which engages a projection 28 on the bracket 11 which supports the magnet. The pivot of the magnet 10 is vertically above the armature portion 17 so that normally the magnet will hang vertically as shown in 110

Fig. 1 with its pole pieces directly over the magnetic portion 17 of the armature. With the magnet in this position, the armature 14 will be drawn up by the magnet as shown in Fig. 1. If, however, the electromagnet 24 is energized the magnet 10 will be deflected to the right as shown in Fig. 3, and the armature will be released and drop into engagement with the stopscrew 16 as shown in Fig. 3. Since the armature of the electromagnet 24 acts on the magnet 10 with a leverage which is short as compared with the leverage at which the magnet 10 is held by its armature, I utilize the magnet 23 for assisting the magnet 24. The magnet 23, by pulling downward on the spring arm 22, forces the arm 14 away from the magnet thereby reducing the effort required of the magnet 24. I may, therefore, make the magnet 24 smaller than would otherwise be the case.

Assuming that the parts are in the position shown in Fig. 3, if the magnet is released it will vibrate on its pivot, swinging back and forth through its normal position. Each time the pole pieces of the magnet pass the magnetic portion 17 there is a tendency for the armature to be lifted but the force is not applied sufficiently long to lift it. As the arm continues to vibrate, however, the amplitude of the movement gradually decreases until a point is reached where the force is sufficient to attract the armature arm. At this point the armature arm will be lifted into contact with the magnet which will thereupon stop vibrating and the switch 18 controlled by the armature will be operated.

In Fig. 3 I have shown my device utilized as a time-limit overload relay for controlling the low voltage coil 29 of the circuit breaker 30. The winding of the electromagnet 24 is connected in series with the winding 23 and the circuit of these two magnets is controlled by an overload relay 31. Under normal conditions, the electromagnet 24 being energized, will hold the pivoted member 27 in a deflected position as shown in Fig. 3 and the switch contacts 20 and 21 will be held in firm contact by the spring member 22 assisted by electromagnet 23. On the occurrence of an overload, however, electromagnets 23 and 24 will both be deenergized. The effect of the deenergization of the magnet 24 is to release the pivoted magnet and allow it to swing freely on its pivot but the deenergization of the magnet 23 has no practical effect. If the overload should only continue for a short time, the overload relay will drop and restore the original conditions, but if the overload persists beyond the time which is predetermined, the magnet 10 which is swinging and all the time approaching a stop, 65 will reach a point where the armature 14

will be attracted, thereby opening switch contacts 20 and 21 against the pressure of spring arm 22 and tripping out the circuit breaker. When normal conditions are restored to the line, the electromagnet 23 being energized, forces the arm 14 slightly away from the magnet 10 and at the same time the energization of electromagnet 24 deflects the magnet 10 so as to be in readiness for the next overload. I find that the 75 operation of the device is improved by reducing the width of the pole faces of the magnet 10 and of the armature as much as possible in the direction of vibration, thereby reducing the length of the interval 80 during which the full force of the magnet is effective in the armature. As shown, I do this by rounding the pole ends of the magnet and using a cylindrical member for an armature. It will be seen that I have 85 provided a very simple device for giving a very definite time interval and while I have described the principle of operation of my invention, together with the apparatus which I now consider to represent the best 90 embodiment thereof, I desire to have it understood that the apparatus shown is only illustrative, and that the invention can be carried out by any other means.

What I claim as new and desire to secure 95 by Letters Patent of the United States, is:—

1. A time element device comprising a magnet and an armature normally attracted into contact with each other and means for causing one of said parts to reciprocate with reference to the other through the normal position at a gradually decreasing amplitude until the magnetic attraction causes movement into contact.

2. A time element device comprising a 105 magnet, a movable armature normally attracted thereby, means for causing one of said parts to reciprocate through the normal position at a gradually decreasing amplitude until the magnetic attraction causes the 110 armature to move into contact with the magnet.

3. A time element device comprising a pivoted magnet, an armature normally attracted thereby, means for causing the magnet to reciprocate through its normal position at a gradually decreasing amplitude until the magnetic attraction causes the armature to be attracted into contact with the magnet.

4. A time element device comprising a magnet and an armature normally attracted into contact with each other and electromagnetic means for initiating a reciprocatory movement of one of said parts with reference to the other through the normal position at a gradually decreasing amplitude until the magnetic attraction causes movement into contact.

5. A time element device comprising a 130

5 pivoted magnet, an armature normally attracted thereby and electromagnetic means for initializing a reciprocatory movement of the magnet on its pivot through its initial 5 position at a gradually decreasing amplitude until the magnetic attraction causes the armature to be attracted into contact with the magnet.

6. A time element switch comprising a 10 magnet and an armature normally attracted into contact with each other, means for causing one of said parts to reciprocate with reference to the other through the normal position at a gradually decreasing amplitude 15 until the magnetic attraction causes movement into contact, and a switch actuated by said movement.

7. A time element switch comprising a 20 magnet and an armature normally attracted into contact with each other, means for causing one of said parts to reciprocate through the normal position at a gradually decreasing amplitude until the magnetic attraction causes movement of the other part, and a 25 switch actuated by said movement.

8. A time element switch comprising a pivoted magnet, an armature normally attracted thereby, means for causing the magnet to reciprocate on its pivot through its 30 normal position at a gradually decreasing amplitude until the magnetic attraction causes the armature to be attracted into contact with the magnet, and a switch operated by the armature.

35 9. A time element switch comprising a pivoted magnet, an armature normally attracted thereby, electromagnetic means for initializing a reciprocatory movement of the magnet on its pivot through its normal position at a gradually decreasing amplitude until the magnetic attraction causes the armature to be attracted into contact with the

magnet, and a switch operated by the armature.

10. A time element switch comprising a 45 magnet and an armature, one of which is pivoted, normally attracted into contact with each other, an electromagnet for deflecting the pivoted part from normal and subsequently releasing it so that it will reciprocate through its normal position at a gradually decreasing amplitude until the magnetic attraction causes the armature to be attracted into contact with the magnet, and a 50 switch operated by the armature. 55

11. A time element switch comprising a permanent magnet pivoted to vibrate freely, a movable armature normally attracted by said magnet, and an electromagnet arranged to deflect the permanent magnet from its 60 normal position and release it when the condition of the magnet is reversed so that the permanent magnet will vibrate through its normal position at a gradually decreasing 65 amplitude until the magnetic attraction causes the armature to be attracted into contact with the magnet.

12. A time element switch comprising a pivoted magnet an armature normally attracted thereby, an electromagnet arranged 70 to deflect the permanent magnet from its normal position and release it when the condition of the magnet is reversed so that the permanent magnet will vibrate through its 75 normal position at a gradually decreasing amplitude until the magnetic attraction causes the armature to be attracted into contact with the magnet, a switch operated by the armature and an electromagnet energized simultaneously with the deflecting 80 electromagnet for controlling the armature.

In witness whereof, I have hereunto set my hand this 15th day of February, 1918.

LOUIS W. THOMPSON.
